UNITED STATES PATENT OFFICE.

EDWARD J. HARVEY, OF RACINE, WISCONSIN.

BOLSTER-SPRING.

1,170,253.

Specification of Letters Patent.

Patented Feb. 1, 1916.

Application filed June 13, 1914. Serial No. 844,857.

To all whom it may concern:

Be it known that I, EDWARD J. HARVEY, a citizen of the United States, residing at the city of Racine, county of Racine, and 5 State of Wisconsin, have invented new and useful Improvements in Bolster-Springs, of which the following is a specification.

My invention relates to improvements in bolster springs for wagons.

10 The object of my invention, is among other things, to so construct the box supporting bars, with which the springs are connected, that the point of contact of the springs with such bars will be increased as 15 the weight of the load increases, whereby the strain will be extended from the center toward the respective ends of said bars, as the latter are depressed by the load, and whereby the resistance of the spring to the 20 load will be increased as the point of contact of the spring with the bars is increased, and also whereby I am enabled in some cases to use a single plate only in the construction of the respective spring, 25 and whereby a less number of plates are necessary than would otherwise be required for supporting a given load. It is a well known fact, that springs as ordinarily constructed to support a heavy load, would be 30 too rigid to use with comfort with a light load. In other words, heavy springs are too rigid to use with comfort when subjected to a light load, while by my improvements a light spring which may be used with com- 35 fort with a light load becomes more rigid in proportion to the weight upon it, and consequently a given bolster spring thus made is adapted to be used with both light and heavy loads.

40 My invention is further explained by reference to the accompanying drawings, in which—

Figure 1 represents a side view showing the spring as it appears before it is subjected to the weight of a load. Fig. 2 represents the same device showing the spring as it appears under pressure of a load. Fig. 3 is a vertical section drawn on line x , x of Fig. 1, and Fig. 4 is a vertical section drawn 50 on line y , y of Fig. 1.

Like parts are identified by the same reference numerals throughout the several views.

1 is a wagon bolster of ordinary construction.

55 2 represents the bolster spring, the respective ends of which are pivotally connected with the bolster 1 through the U-shaped stirrups 3. The respective ends of the springs are provided with circular bends 4, which inclose the ends of the stirrups 3, while the center portion of the stirrups rests upon the bolster 1 and are retained in place by the plates 5 and circular brackets 6. To the center of each spring 60 is rigidly secured a bar 7, by the U-shaped keepers 8 and nuts 9, which nuts have threaded bearings on the respective ends of the keepers 8. The lower side of the bars 7 are straight and are adapted as the springs 65 are compressed, from the position shown in Fig. 1 to that shown in Fig. 2, to be brought in direct contact with the upper side of the springs, as shown in said Fig. 2, whereby the 70 area of the point of contact upon which the 75 load rests is increased in proportion to such load and whereby the rigidity of the spring is also increased in proportion to its load. The respective ends of the bars 7 are preferably connected together by metal plates 80 10 and bolts 11.

75 It will be understood that the ordinary wagon box, not shown, is adapted to rest at its respective ends upon the bars 7, and that such box is free to move upward and 85 downward with the load between the stakes 12, 12 as the springs are compressed and expanded by the jarring movement of the vehicle with which they are connected.

Having thus described my invention what 90 I claim as new and desire to secure by Letters Patent, is—

95 The combination with a bar having a flat surface, of a leaf spring secured to said flat surface of the bar, said spring projecting outwardly from the point of connection longitudinally of the bar and diverging therefrom in a continuous curve from the portion in contact with the bar substantially to the outer end of the spring, the 100

form and resilience of said spring being such that the area of continuous contact with the bar will progressively increase in direct proportion to the load and throughout the entire length of said flat surface opposed to the spring, whereby the spring may be progressively reinforced by the bar from the point of connection to the end of the area of contact in accordance with the

load to be carried, substantially as de- 10 scribed.

In testimony whereof I affix my signature in the presence of two witnesses.

EDWARD J. HARVEY.
